UNITED STATES PATENT OFFICE.

HERBERT D. SWIFT, OF NEW YORK, N. Y., ASSIGNOR TO INTERNATIONAL AUTOMATIC APPLIANCE CORPORATION, A CORPORATION OF NEW YORK.

METHOD OF AND APPARATUS FOR TREATING METAL.

1,387,023.

Specification of Letters Patent. Patented Aug. 9, 1921.

Application filed March 27, 1920. Serial No. 369,361.

To all whom it may concern:

Be it known that I, HERBERT D. SWIFT, a citizen of the United States, and a resident of the borough of Manhattan, city, county, and State of New York, have invented certain new and useful Improvements in Methods of and Apparatus for Treating Metal, of which the following is a specification.

This invention relates to the annealing of metals and is particularly adapted for annealing metals as they come from the rolling mills, irrespective of the particular shape of the metal, that is to say, whether in the form of a bar, strip or wire. It is to be understood, therefore, that in its broadest aspects the present invention is directed to a method of and apparatus for use in connection with any metal to be annealed.

It has been common practice prior to this invention to make up a number of coils of metal after coming from the rolling mills and to take these metal coils and place them, one on top of the other, in an annealing oven for a predetermined length of time, depending upon the degree of temper desired. These metal coils are then taken from the annealing oven and cleaned, sometimes necessitating uncoiling of the metal, cleaning it, and then coiling it up again. This method is unsatisfactory for obvious reasons, inasmuch as a great deal of time is consumed in the coiling operation which time is greatly increased of course, in the event of the metal being cleaned in the manner referred to, and it is not always possible to succeed in annealing the metal uniformly throughout, that is to say, not only may each coil be improperly annealed but there may be a lack of uniformity comparing one coil with another.

In annealing bar metal it is common practice to place the same in an annealing oven where it is subjected to a predetermined temperature until the metal is annealed sufficiently.

All of these methods are unsatisfactory, however, as a great deal of time is necessarily consumed in the annealing operation and furthermore it seems to be practically impossible to get a uniformly annealed product.

It is an object of the present invention,

therefore, to provide a method of and apparatus for annealing metals wherein these defects are overcome.

A further object of the invention is to provide a method of and apparatus for annealing metals wherein not only will the metal be annealed uniformly throughout but may be annealed while in motion, thus effecting a substantial saving in time resulting in an increased production.

Another object of the invention is the provision of a method of and apparatus for annealing metals whereby the necessity of coiling the metal up before being annealed is eliminated, the metal in the present instance being taken from the rolling mills, and led directly into the annealing chamber, and after being annealed and not until then, coiled up. If desired and should it be necessary to clean the metal after annealing, this may be done as the metal comes from the annealing chamber, so that there will be the continuous process of rolling the metal, annealing, cleaning if necessary, and finally coiling in a finished condition.

A further object of the invention is the provision of means whereby the metal while being annealed may be passed through a set of reducing rolls thereby effecting a saving in rolling or drawing costs.

Other and further objects will be apparent from the detailed description to follow.

In its broadest aspects the present invention comprises a method and apparatus whereby an electric current, either impressed or induced, and of sufficient amperage, is passed through a closed circuit, part of which is composed of the metal to be annealed, for a sufficient length of time to generate an annealing heat in said metal.

In the accompanying drawing I have illustrated in perspective an embodiment of my invention wherein a plurality of metal sections may be annealed simultaneously.

Referring to the drawing in detail, 54 designates the metal shell of a transformer, the coils 55 constituting the primary winding thereof encircling the central leg 56. Passing through the spaces each side of the leg 56 are transversely extending contact bars 58, these bars being supported by suitable columns 59. Rollers 60 are carried at each

- end of these bars. Immediately above the bars are rollers 61. The metal 62 to be annealed may be fed between the contact bars 60 and the rollers 61 and if the primary 55 5 of the transformer be energized by current from the generator 63, current will be induced in the metal sections 62 which will be short-circuited through the contact bars 58 and the metal sections.
10. In order that the annealing temperature may be varied I have provided resistance coil 64 adapted to be cut in and out or varied by the arm 65.
- The rollers 60 and 61 are preferably, 15 though not necessarily, provided with peripheral grooves 66 to grip the metal sections as the same are fed through the apparatus. It will be obvious that if desired the rollers 61 may be spring pressed.
20. At times it may be desirable to reduce the metal during the annealing operation and to this end I have provided reducing rollers 67 and 68 mounted on suitable supports 69. It will be understood from the drawings that 25 a set of reducing rollers for each metal section may be provided. These rollers are positioned intermediate the contact bars 58 so that the metal sections will be annealed and reduced simultaneously which is of distinct 30 advantage in that otherwise after reduction the metal sections would necessarily have to go through the annealing operation again.
- From the foregoing it will be seen, that I 35 have provided a method of and apparatus for annealing metal sections wherein the metal to be annealed is heated by short-circuiting an electric current either induced or impressed through the same whereby one or more metal sections may be annealed simultaneously. It will be obvious also that I 40 have provided a method and apparatus whereby the metal may be reduced during the annealing operation. Furthermore I have provided means whereby the annealing 45 temperature may be varied as desired.
- While I have illustrated an embodiment of my invention, it is to be understood that changes may be made in the details of construction illustrated within the purview of 50 the invention.
- In this illustration two strips or sections of metal have been illustrated which will be annealed simultaneously but it is to be understood that more than two strips or sections may be annealed simultaneously if desired.
- What is claimed as new is:
1. The method of annealing metal which method consists in inducing in the metal to 60 be annealed an electric current of sufficient amperage and maintained for a sufficient length of time to generate an annealing heat in said metal.
2. The method of annealing metal which method consists in inducing in a plurality 65 of metal sections simultaneously electric current of sufficient amperage and maintained for a sufficient length of time to generate an annealing heat in said metal sections.
3. The method of treating metal which 70 consists in generating an annealing heat in the metal by passing an electric current of sufficient amperage and for a sufficient length of time through a closed circuit a part of which is composed of the metal to be 75 annealed to generate an annealing heat in said metal, and at the same time passing the metal through reducing rolls.
4. In an apparatus of the class described, 80 the combination of a primary winding, contact bars for the reception of metal sections to be annealed, and means for energizing said primary winding whereby induced current will be short-circuited through the metal sections to anneal the same.
5. In an apparatus of the class described, 85 the combination of a primary winding, a contact bar on opposite sides of said primary winding, and a pair of rollers supported at each end of said contact bars whereby when the primary winding is energized an induced current will be short-circuited through metal sections bridging said contact bars and between said rollers.
6. In an apparatus of the class described, 90 the combination of a primary winding, a contact bar on opposite sides of said winding, and reducing means intermediate said contact bars, whereby when said primary winding is energized an induced current will 100 be short-circuited through metal sections bridging said contact bars and passing through the reducing means.
7. In an apparatus of the class described, 105 the combination of means for annealing metal sections and means for rolling the sections during the annealing operation.
8. In an apparatus of the class described, 110 the combination of means for short-circuiting an electric current through a section of metal to anneal the same and means for simultaneously reducing the cross-section of said metal.
9. In combination a transformer frame, a primary winding intermediate the ends of 115 said frame, means for energizing said winding, a contact bar on each side of said winding intermediate it and the end of said frame, and metal sections bridging said contact bars.
10. In combination, a transformer frame, a primary winding supported thereby, contact bars between said winding and the ends of said frame, a pair of rollers at each end of said contact bars provided with peripheral grooves, and metal sections adapted to be received by said grooves and to bridge said contact bars, whereby when said 120 125

primary winding is excited a current will be induced in the metal sections and short-circuited thereby.

11. In an apparatus of the class described, 5 the combination of a primary winding, contact bars for the reception of metal sections to be annealed, means for energizing said primary winding whereby induced current will be short-circuited through the metal

sections to anneal the same, and means for 10 rolling the metal sections during the annealing operation.

12. The method of treating metals which method consists in simultaneously annealing and reducing the metal. 15

This specification signed this 25th day of March, 1920.

HERBERT D. SWIFT.
